Primary Examiner — Selina Sikder*(74) Attorney, Agent, or Firm* — Locke Lord LLP;
 Howard M. Gitten(57) **CLAIM**

The ornamental design of a control panel with touchscreen, as shown and described.

DESCRIPTION

FIG. 1 is a front elevation view of a control panel with touchscreen, in accordance with the invention;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevation view thereof; and,

FIG. 7 is a perspective view of the control panel with touchscreen, in accordance with the invention;

FIG. 8 is a front exploded view of the control panel with touchscreen, in accordance with the invention; and,

FIG. 9 is a rear exploded view of the control panel with touchscreen, in accordance with the invention.
